(57) **CLAIM**

The ornamental designs for a flat-sided bottle, as shown and described.

DESCRIPTION

FIG. 1 is a perspective view of a first embodiment of a flat-sided bottle, said first embodiment having a lipped opening.

FIG. 2 is a front elevational view of the flat-sided bottle of FIG. 1. The left, right and rear elevational views of the flat-sided bottle are all identical to the front view.

FIG. 3 is a top plan view of the flat-sided bottle of FIG. 1. FIG. 4 is a bottom plan view of the flat-sided bottle of FIG. 1.

FIG. 5 is a perspective view of a second embodiment of a flat-sided bottle, said second embodiment having a threaded opening.

FIG. 6 is a front elevation of FIG. 5, the left, right and rear elevations are the same except for the bottle neck.

FIG. 7 is a top plan view of the flat-sided bottle of FIG. 5; and,

FIG. 8 is a bottom plan view of the flat-sided bottle of FIG. 5.

The portions of the bottle neck of the second embodiment that are not shown in the drawings do not form part of the claimed design.
